United States Patent Office

Des. 180,136
Patented Apr. 23, 1957

180,136

AIRPLANE

Philip A. Colman, Beverly Hills, Eugene C. Frost, Burbank, and Arthur E. Flock, Sherman Oaks, Calif., assignors to Lockheed Aircraft Corporation, Burbank, Calif.

Application May 26, 1954, Serial No. 30,665

Term of patent 14 years

(Cl. D71—1)

Des. 180,136

PAGE 2

Fig. 1 is a front elevation view of an airplane showing our new design;

Fig. 2 is a side elevational view thereof;

Fig. 3 is a top view of the airplane as shown in Fig. 2;

Fig. 4 is a rear elevation thereof;

Fig. 5 is a bottom plan view of the airplane as shown in Fig. 2; and

Fig. 6 is a perspective view of the airplane.

The essential features of our design reside in the portions shown in full lines.

We claim:

The ornamental design for an airplane, as shown and described.
